UNITED STATES PATENT OFFICE

KING H. MC LAURIN, OF DUQUESNE, PENNSYLVANIA

CLAY GUN CLAMPING MECHANISM

Application filed December 24, 1930. Serial No. 504,585.

In blast furnace operations it is common practice to suspend the clay gun for plugging the iron notch or tap hole on a radius arm or boom, the gun being swung into position and clamped securely in place before the plugging operation is started to brace the gun against rebound or reactions set up when the gun is discharged. The clamping arms or levers are usually primarily actuated by means of a power cylinder, and the time required to effect the clamping of the gun is directly proportional to the length of the piston stroke. With certain types of cylinders, such as the oil-operated type, delay is experienced due to the comparatively slow movement of the piston, and as will be understood by those having a knowledge of the art, it is desirable to effect the clamping operation as expeditiously as possible.

The present invention provides means in the form of cooperating lever mechanism adapted to operate between the power cylinder or prime mover and the clay gun clamping arms which multiplies the stroke of the piston and at the same time applies the pressure to the clamping arms during the termination of the piston stroke when the most effective leverage is obtained and at which time the said arms are under load, thereby permitting the employment of a comparatively short-stroke prime mover and greatly reducing the time required for clamping the gun in plugging position and increasing the force available for a given cylinder pressure. The mechanism is simple in construction and operation and may be readily installed in connection with the usual type of clay gun and its appurtenances.

Other objects and advantages will become more apparent in view of the following description taken in conjunction with the drawings, wherein:

Figure 1 is a view in side elevation of mechanism embodying the features of the invention.

Figure 2 is a plan view of parts shown in Figure 1.

The reference numeral 5 designates a clay gun of the conventional type which is shown suspended from a boom 6 attached to the fur-

nace column 7, the gun being swung into position either manually or automatically when plugging is desired, to bring its nozzle into position relatively to the iron notch or tap hole indicated at 8, said nozzle being clamped against the notch opening by means of clamping arms 9 which are mounted on a horizontal shaft 10, the latter being mounted at opposite extremities in bearing brackets 11 attached to columns 7 and 7^a, the invention being primarily concerned with the operation of these clamping arms 9, as will be understood.

The shaft 10 and consequently the arms 9 are primarily actuated by a power cylinder 12, which is mounted to turn or swing bodily in an arcuate path on a swivel pin 13 carried by a bearing bracket which may be secured to the column 7. The cylinder 12 is provided with a piston 14 and a piston rod 15, an eye 16 being adjustably mounted on the lower end of said rod and carrying a guide pin 17. This guide pin 17 is adapted for travel in slots 18 formed in a pair of guide plates 19 and also in slots 20 formed in a forked operating lever 21, the said plates being framed together in parallel relation by means of shouldered bolts 22. These plates are supported in fixed position by the shaft 10, which passes through the lower end corner portion of said plates, and an adjustable eye bolt 23, which is adjustably mounted in a bracket 24 secured to the column 7; while the lever 21 is keyed to the end of shaft 10 and operates between the plates 19. The adjustable eye 16 is fitted to slide between the inner faces of the fork of the operating lever 21.

It will be noted that the slots 18 in the fixed plates 19 are inclined downwardly to their outermost extremities, where they turn abruptly at an approximate ninety degree angle, while the radial movement of the forked operating lever 21 is transmitted directly to the clamping arms 9 through shaft 10, the gun 5 being provided with contact members 25 with which the clamping arms cooperate in clamping the said gun in plugging position.

The operation of the mechanism will be

readily understood. Assuming that the clamping arms 9 are in their uppermost position, the piston 14 will then be at the top of the cylinder 12 ready for its forward or downward stroke. When power or fluid pressure is applied to the cylinder 12, the guide pin 17 is guided in the path formed by the inclined slots 18, which causes the end of the piston rod 15 to swing laterally more rapidly than it can move downwardly, while the guide pin 17 carries with it the lever 21, producing a comparatively rapid partial revolution of the shaft 10 under no load and a correspondingly rapid action of the clamping arms 9, which reach the point of contact 25 on the clay gun 5 when the guide pin 17 is at the termination of the inclined portion of the slots 18. The load is now being applied on the clamping arms 9, and the guide pin 17 moves at an angle of approximately ninety degrees to its initial path and the pressure of the piston is exerted directly on the end of the operating lever 21, thus producing maximum pressure of the clamping arms 9 on the contact members 25. The cylinder pressure is thus applied to the clamping arms when the most effective leverage is obtained, greatly increasing the force available for a given cylinder displacement, and said arms are swung rapidly into clamping position while employing a comparatively short piston stroke, thereby greatly reducing the time required for the clamping operation.

What I claim as new is:

1. Clamping mechanism for clay guns, comprising movable clamping arms movable to and from a position of engagement with the gun, a prime mover for said arms, and means interposed between said prime mover and said arms for transmitting pressure thereto indirectly while under no load and direct pressure thereto when the clamping load is applied, the load pressure being applied at substantially right angles to the no-load pressure.

2. Clamping mechanism for clay guns, comprising movable clamping arms movable to and from a position of engagement with the gun, prime moving means for said arms comprising a pivotally mounted fluid pressure cylinder, a piston in said cylinder and a rod connected to said piston, and means cooperating with said rod for guiding said cylinder in an arcuate path before the cylinder is delivering load pressure, the cylinder reaching the end of its arcuate travel when the load is applied.

3. Clamping mechanism for clay guns, comprising movable clamping arms movable to and from a position of engagement with the gun, a prime mover for said arms, and means interposed between said prime mover and said arms for multiplying the stroke of said prime mover.

4. Clamping mechanism for clay guns, comprising movable clamping arms movable to and from a position of engagement with the gun, a pivotally-mounted fluid pressure cylinder for said arms, a piston in said cylinder and a rod connected to said piston, and means for guiding the head of said rod laterally in an inclined plane when the piston is delivering no-load pressure and at substantially right angles to said plane when the piston is under load.

5. Clamping mechanism for clay guns, comprising clamping arms movable to and from a position of engagement with the gun, a pivotally-mounted fluid pressure cylinder for said arms, a piston in said cylinder and a rod connected to said piston, and a slotted member cooperating with said rod for guiding the head of the latter laterally in an inclined plane when the piston is delivering pressure under no load and at substantially right angles to said plane when the piston is delivering pressure under load.

6. Clamping mechanism for clay guns, comprising clamping arms movable to and from a position of engagement with the gun, a shaft on which said arms are mounted, a slotted lever connected to said shaft, a slotted member cooperating with lever, and a pivotally-mounted fluid pressure means having an operative connection with said lever and also with said slotted member.

7. Clamping mechanism for clay guns, comprising clamping arms movable to and from a position of engagement with the gun, a shaft on which said arms are mounted, a slotted lever connected to said shaft, a pivotally-mounted fluid pressure cylinder provided with a piston and a piston rod having a head mounted to travel in the slot of said lever, and means for guiding said head in such a path as to vary the mechanical advantage of said lever during the stroke of said piston.

8. Clamping mechanism for clay guns, comprising clamping arms movable to and from a position of engagement with the gun, a shaft on which said arms are mounted, a lever connected to said shaft, and means for applying initial angular pressure and final direct pressure to said lever.

9. Clamping mechanism for clay guns comprising clamping arms, a shaft on which said arms are mounted, a slotted lever connected to said shaft, at least one slotted guide member mounted adjacent said lever and a pivotally-mounted fluid pressure cylinder provided with a piston and piston rod having a head provided with means for its guidance by the slots of said lever and said guide member.

10. Clamping mechanism for clay guns comprising clamping arms, a shaft on which said arms are mounted, a slotted lever connected to said shaft, a slotted fixed guide means mounted adjacent said lever and a

pivottally-mounted fluid pressure cylinder provided with a piston and piston rod having a head provided with means for its guidance by the slots of said lever and said fixed guide 5 means.

In testimony whereof, I have hereunto set my hand.

KING H. McLAURIN.
